UNITED STATES PATENT OFFICE.

HECTOR RABEZZANA, OF FLINT, MICHIGAN, ASSIGNOR TO A C SPARK PLUG COMPANY, OF FLINT, MICHIGAN, A CORPORATION OF MICHIGAN.

STENCILING MACHINE.

Application filed April 29, 1922. Serial No. 557,276.

To all whom it may concern:

Be it known that I, HECTOR RABEZZANA, a subject of the King of Italy, and a resident of Flint, county of Genesee, and State of Michigan, have invented certain new and useful Improvements in Stenciling Machines, of which the following is a full, clear, concise, and exact description, such as will enable others skilled in the art to which the invention relates to make and use the same, reference being made therein to the accompanying drawings, which form a part of this specification.

My invention relates to stenciling machines designed to apply a pattern, design or figure, to an article by the use of a stencil having an opening or openings therein corresponding with the pattern, and through which openings a suitable coloring medium may pass to the surface to be stenciled; and the object thereof is to provide an improved stenciling machine designed to apply a trade mark or trade name, or equivalent identifying character or device to the porcelain or equivalent material insulating members of spark plugs in an effective manner, the design or figure being commonly applied to the insulating members before they are glazed so that the impression produced by the stencil appears under the glaze in the finished insulator after it had been fired. The particular condition or state of the insulators, however, is in no way involved in the invention to which this present application relates; this present invention relating to and comprehending a machine which, as a matter of course, may be used in the stenciling of any kind of articles adapted to receive impressions from stencils and the form of which is such that the machine may operate upon them.

The drawings accompanying and forming a part of this application illustrate the best form of my invention now known to me; although the invention may be embodied in other particular structures, and the same is regarded as including all such variations and modifications of the particular embodiment thereof illustrated and hereinafter described as come within the scope of the concluding claims, wherein the distinguishing features wherein my invention consists are particularly pointed out.

In the drawings:

Figure 1 is a view partly in side elevation

and partly in section upon a vertical central plane, showing my improved stenciling machine and illustrating its intended use.

Figure 2 is a similar view showing the invention in plan. 60

Figure 3 is a fragmentary view showing certain parts of the machine upon a larger scale, and upon a vertical plane as in Figure 1.

Figure 4 is a view quite similar to Figure 3 as regards the parts shown, but in plan, and provided with arrows to indicate the directions of movement of the parts appearing in said view. 65

In the drawings the reference numeral 5 designates a suitable base or pedestal and 6 a hollow housing or frame element or section secured to the upper end of the base by means of cap screws 7, or otherwise, and to the upper end of which housing the lower end of a table section is secured as by means of similar screws 8; the said last named section comprising a lower tubular portion 9 of some little length, and an upper substantially flat portion 10 having a peripherally extending trough 11, as is usual in machine tables. 70

Rotatably supported by ball or equivalent bearings 12, 13, 14 carried by the table section is a vertically arranged hollow sleeve or shaft 15 having a flange 151 at its upper end; and which shaft is driven by a worm wheel 16 secured upon its lower end, which in turn is driven by a worm 17 supported in bearings provided in the frame member 6 and meshing with said worm gear. Inasmuch as a driving gear has to be provided for the said shaft 15 within the frame section or housing 6 the worm gear 16 is shown as secured to the hub of a bevel gear 18, 95 which gear in turn is secured to the lower end of the shaft 15; although as a matter of course these two gears may be entirely separate from one another and independently secured to the shaft in question, should such a construction be deemed preferable or necessary. 100

Secured to the flange 151 is an annular horizontally disposed carrier or head 19 having a series of spaced apart lower and upper bearings 20, 21 located adjacent and regularly arranged about its periphery; twelve such pairs of bearings being present in the particular machine illustrated. These pairs of bearings support a corresponding num- 105
110

ber of vertical shafts or spindles 22, which carry or support the insulating member to be stenciled, as shown in Figure 1, each spindle having a pinion 23 secured thereto and located between the bearings for the shaft in question; and a single gear 24 meshes with all these pinions so as to rotate all the shafts, as well also as the insulators supported by their upper ends, at one and the same time. This gear 24 is secured to the upper end of a vertically arranged shaft 25, which is rotatably supported within and extends through the hollow shaft 15 aforesaid, as by ball or equivalent bearings 26, 27 at its upper and lower ends; and a worm wheel 28 is secured to the lower end of said shaft and acts to drive the same to thereby rotate the several spindles aforesaid as will be appreciated. The worm wheels 16 and 28 are obviously both located within the hollow housing 6; and said last mentioned gear is driven by a worm 29 which, like the worm 17, is supported in suitable bearings provided for it in the said housing or frame. The lower end of this housing 6 is shown as closed by a plate 61, the periphery of which is held between the lower end of the housing and of the upper end of the pedestal 5, and which plate 30 serves as a support for the lower bearing 27 above referred to.

Resting upon the carrier 19 is a cover 30 having peripherally spaced openings corresponding in number with the spindles 22, and into which openings the upper ends of said spindles extend; and each opening is surrounded by an upwardly extending annular flange 31. The spindles 22 are of considerably less diameter than the openings and each carries upon its upper end an insulator supporting member which serves as an immediate support for the insulator carried by the shaft; and which member is shown as having a hollow tubular portion 32 fitting over the end thereof so as to rotate therewith and which tubular portion fits loosely within its opening in the cover 30, a depending petticoat 33 surrounding the flange 31 so as to prevent water from running through the openings in the cover and into the interior of the carrier where the gearing for rotating the spindles and the insulator supporting members is located, and having also an upwardly extending pin 34 upon which an insulating member to be stenciled may be placed; the insulating members when they reach the machine to which this invention relates having been already provided with axially extending passages of approximately the same diameter as the pins 34, so that when said members are placed upon the insulator supports the friction between the parts will be sufficient to insure rotation of the insulators at the same speed as that at which the

spindles 22 are driven. As will herein-after appear nothing but a spray of liquid carrying a suitable pigment touches the insulating members at any time, and no considerable driving force has to be communicated to said members; the friction due to the weight of the insulating members being, in fact, sufficient to insure their being driven from the spindles in the manner before explained. 75

Supported beneath the table 10 in a split collapsible clamping bearing 35 is an adjustable bracket 36 having an annularly disposed split clamping bearing 37 at its free end, and within which last mentioned bearing an adjustable tubular sleeve 38 is secured; said sleeve having ball or equivalent bearings at its upper and lower ends, at 39, 40, wherein an angularly arranged shaft 41 is rotatably supported, said shaft 80 being driven from the bevel gear 18 through a pinion 42 in mesh therewith. This pinion 42 is carried by a short horizontal shaft 43 rotatable in a bearing provided for it in the housing 6, and the same is operatively connected with the inclined shaft 41 through a suitable universal joint 44, which is shown as enclosed within a suitable casting 45. 90

Secured to the upper end of the shaft 41 so as to be driven thereby is a rotating inclined stencil wheel 46 having a plurality of stencils spaced about the rim or periphery thereof; six stencils designated by the numerals 47 being used in the embodiment 100 of my invention illustrated and herein described. The speed ratio of the gears 18, 42 being two to one, it therefore follows that when the machine is properly adjusted the stencils 47 and insulators carried by the pins 34 will move alongside and close to one another at the place where the peripheries of the carrier 19 and stencil wheel 46 approach the closest to one another. These two members rotate in opposite directions so that the stencils and the insulating members travel in the same direction as they approach and move alongside one another, the insulating members and stencils being assumed to be moving away from the observer at the time when they are closest together and moving alongside one another in the machine illustrated. 11

The stencils 47, the spindles 22 and the insulators carried thereby, therefore move as such velocities, and the speed at which the said spindles and insulators are rotated by the gear 24 and pinions 23 is such that rolling of the stencils and of the surfaces of the insulators upon which the pattern of the stencils is placed relative to one another, similar in all respects to the rolling between a gear and a pinion with which it meshes, occurs when the machine is in operation; so that blurring of the figure pro- 12 13

duced by the stencil upon the insulator, due to difference in rate of movement between the stencil and insulator surface printed upon, will be obviated or reduced to a negligible amount.

The stencil wheel and carrier have necessarily to be positively and definitely geared together in order that the insulators and the stencils will come opposite one another as 10 said elements rotate, and when the stencils and insulators are at the inner adjacent portions of said elements, and this is accomplished by the gears 18 and 42 in mesh with one another, the worm 17 being in fact the 15 driving member so far as carrier and stencil wheel 46 are concerned. This worm, however, is itself driven through a suitable belt or equivalent member from the worm 29, which last mentioned worm is driven 20 from an electric motor 48 of any suitable type through a belt 49; this arrangement providing a convenient and effective speed reducing scheme for the motor and an arrangement whereby the high speed necessary 25 at the spindles 22 is readily secured.

A spray of a stenciling liquid, such, for example, as a suitable pigment dissolved or held in suspension in water is produced by a nozzle 50 to which suitable air and liquid 30 supply conduits lead, which spray is directed against the inner sides of the stencils and passes through the openings therein and thus reaches the surface of the insulators to be stenciled. In practice the greater part 35 of the total volume of atomized liquid is arrested by perforated baffle plates 51, 52; the latter being shown as provided by an end wall of a casing or hood 53 within which the atomizing nozzle is located. The 40 nozzle is shown as supported from the bracket 36 as a matter of convenience although the manner of supporting the nozzle, as well also as the number and arrangement of the intercepting baffles, are matters of secondary importance not involved 45 in my invention.

Such atomized stenciling liquid as does not pass through the openings in the baffles 51, 52 runs down the bottom of the hood 53 and returns through a pipe 54 to a storage 50 tank 55 from which the same is returned to the nozzle 50 by a suitable pump; and a washing tank 56 containing clean water is commonly so arranged that the periphery 55 of the stencil wheel 46 passes through it to thereby prevent obstruction or gumming up of the openings in the stencils due to evaporation of the liquid in which the pigment of the stenciling medium is dissolved, and 60 with which the periphery of the wheel and the stencils are constantly wetted when the machine is in operation; and which stenciling liquid if not washed off from the stencil, due to evaporation thereof continually 65 taking place, would produce a deposit of

the solid pigment material employed at and about the openings through the stencils such as would be likely to interfere with the operation of the machine.

While I have described my invention as 70 a stenciling machine adapted to impress a figure of relatively small area and of distinctive form or outline upon a comparatively large surface, it will be appreciated that the stencils may be of various forms to 75 produce various figures or designs, and may be of such length, circumferentially of the stencil wheel, that the resulting figure will extend throughout the entire circumference of the articles stenciled; and that a film of 80 liquid covering the entire articles operated upon may be applied thereto by making the openings in the stencil wheel of such size as to permit the sprayed material to impinge thereupon while they are rotated throughout 85 an entire rotation by the spindle driving mechanism hereinbefore described and explained.

Having thus described and explained my invention, I claim and desire to secure by 90 Letters Patent:

1. In a stenciling machine, a rotatable carrier; means for supporting a plurality of articles to be stenciled in spaced relation with one another about the periphery of 95 said carrier; a unitary rotatable stencil wheel formed as a single substantially rigid structure and the periphery of which moves adjacent articles to be stenciled carried by said carrier; a plurality of stencils carried by and held in fixed relation to, and spaced about the periphery of said stencil wheel; means for supplying a stenciling material to 100 said stencils; and means for rotating said stencil wheel and said carrier at definite 105 speeds relative to one another.

2. In a stenciling machine, a rotatable carrier; a plurality of spindles carried by said carrier and rotatable in bearings located adjacent the periphery thereof, and which spindles are adapted to support articles to be stenciled; means for rotating said spindles; a rotatable stencil wheel comprising a unitary substantially rigid structure the periphery of which moves adjacent articles to be stenciled supported by said spindles; a plurality of stencils fixedly secured to and spaced about the periphery of said stencil wheel; means for supplying a stenciling liquid to said stencils; and means for 115 rotating said stencil wheel and said carrier at definite speeds relative to one another.

3. In a stenciling machine, an annular carrier rotatable about a vertical axis; a plurality of vertically arranged spindles carried by said carrier and rotatable in bearings located adjacent the periphery thereof; supporting members associated one 125 with each spindle, and which members are adapted to support articles to be stenciled;

pinions carried one by each of said spindles; a rotatable gear wheel arranged within said carrier and adapted to engage the pinions aforesaid to thereby rotate said 5 spindles; a rotatable stencil wheel the periphery of which moves adjacent articles to be stenciled supported by said spindles; a plurality of stencils carried by and spaced about the periphery of said stencil wheel; 10 a nozzle arranged to discharge against said stencils; and means for rotating said stencil wheel and said carrier at definite speeds relative to one another.

4. In a stenciling machine, an annular 15 carrier rotatable about a vertical axis; a plurality of vertically arranged spindles carried by said carrier and rotatable in bearings located adjacent the periphery thereof; supporting members whereby articles to be stenciled may be supported one 20 by each spindle above the upper end thereof; means located within said annular carrier for rotating said spindles and the articles carried thereby; a rotatable stencil 25 wheel the periphery of which moves adjacent articles to be stenciled supported by said spindles; a plurality of stencils carried by and spaced about the periphery of said stencil wheel; a nozzle arranged to discharge 30 against said stencils; and means for rotating said stencil wheel and said carrier at definite speeds relative to one another.

5. In a stenciling machine, a rotatable annular carrier; a vertically arranged tubular 35 shaft whereby said carrier is carried; a plurality of vertically arranged spindles supported by said carrier and rotatable in bearings arranged adjacent the periphery thereof, and which spindles are adapted to 40 support a corresponding number of articles to be stenciled; a rotatable shaft extending through said tubular shaft and provided with means located within said carrier for simultaneously rotating all of said spindles 45 and the articles to be stenciled carried thereby; a rotatable stencil wheel the periphery of which moves adjacent articles to be stenciled carried by said spindles; a shaft whereby said stencil wheel is supported and 50 driven; a plurality of stencils carried by and spaced about the periphery of said stencil wheel; and means for simultaneously driving the three shafts aforesaid.

6. In a stenciling machine, a vertically 55 arranged hollow shaft rotatable in suitable bearings; a carrier secured to the upper end of said shaft and rotatable therewith; a plurality of vertically arranged spindles carried by said carrier and rotatable in bearings located adjacent the periphery thereof; supporting members one at the upper end of each of said spindles and which members are adapted to support articles to be stenciled; 60 pinions secured one to each of said spindles; a shaft extending through the hollow shaft

aforesaid and rotatably supported relative thereto; a gear wheel secured to the upper end of said shaft and meshing with all of said pinions, to thereby rotate the several spindles aforesaid simultaneously; an inclined shaft; a rotatable stencil wheel secured to the upper end of said inclined shaft and the periphery of which moves adjacent articles to be stenciled supported by said spindles; a plurality of stencils carried by 75 and spaced about the periphery of said stencil wheel; a nozzle arranged to discharge against said stencils; and means for driving said three shafts at proper speeds relative to one another.

7. In a stenciling machine, a hollow frame or housing; a tubular member secured to said housing and extending upwardly therefrom; a rotatable tubular shaft extending through said tubular member and into said 80 housing; an annular carrier secured to the upper end of said tubular shaft and having a plurality of rotatable spindles adapted to support articles to be stenciled; a rotatable shaft extending through said tubular shaft 85 and into said housing; means at the upper end of said shaft for rotating said spindles; a rotatable stencil wheel the periphery of which moves adjacent articles to be stenciled supported by said spindles; a plurality of 90 stencils carried by and spaced about the periphery of said stencil wheel; a shaft whereby said wheel is carried; gearing located within said housing and whereby said three shafts are driven; and means for supplying a stenciling material to said stencils.

8. In a stenciling machine, a hollow frame or housing; a tubular member secured to said housing and extending upwardly therefrom; a rotatable tubular shaft extending through said tubular member and into said housing; a worm wheel located within said housing and operatively connected with said tubular shaft; an annular carrier secured to the upper end of said tubular shaft and 100 having a plurality of rotatable spindles adapted to support articles to be stenciled; a rotatable shaft extending through said tubular shaft and into said housing; a second worm wheel located within said housing and operatively connected with said second shaft; means at the upper end of said second shaft for rotating said spindles; an inclined rotatable stencil wheel the periphery 105 of which moves adjacent articles to be stenciled carried by said spindles; a plurality of stencils carried by and spaced about the periphery of said stencil wheel; a shaft whereby said wheel is carried and which shaft extends into said housing and is 110 driven from one of the two shafts aforesaid; two worms supported in bearings carried by said housing and which worms act 115 one to drive each of said worm wheels; means for driving said worms; and means

120
125
130

for supplying a stenciling material to said stencils.

9. In a stenciling machine, a rotatable carrier; means for supporting a plurality of articles to be stenciled in spaced relation with one another about the periphery of said carrier; a unitary rotatable stencil wheel formed as a single substantially rigid structure and the periphery of which moves adjacent articles to be stenciled carried by said carrier; a plurality of stencils carried by and spaced about the periphery of said stencil wheel; means for supplying a stenciling material to said stencils; a washing tank containing a liquid through which said stencil wheel moves; and means for rotating said stencil wheel and said carrier at definite speeds relative to one another.

10. In a stenciling machine, a horizontally arranged rotatable carrier; a plurality of spindles carried by said carrier and rotatable in bearings located adjacent the periphery thereof, and which spindles are adapted to support articles to be stenciled; means for rotating said spindles; an inclined rotatable stenciling wheel, the periphery of which moves adjacent articles to be stenciled supported by said spindles; a plurality of stencils carried by and spaced about the periphery of said stencil wheel; a washing tank containing a liquid through which the periphery of said stencil wheel moves; means

for supplying a stenciling liquid to said stencils; and means for rotating said stencil wheel and said carrier at definite speeds relative to one another.

11. In a stenciling machine, an annular carrier rotatable about a vertical axis; a plurality of vertically arranged spindles carried by said carrier and rotatable in bearings located adjacent the periphery thereof; supporting members associated one with each spindle, and which members are adapted to support articles to be stenciled; pinions carried one by each of said spindles; a rotatable gear wheel arranged within said carrier and adapted to engage the pinions aforesaid to thereby rotate said spindles; a rotatable stencil wheel inclined relative to said carrier and the periphery of which moves adjacent articles to be stenciled supported by said spindles; a plurality of stencils carried by and spaced about the periphery of said stencil wheel; a nozzle arranged to discharge against said stencils; a washing tank adapted to contain a liquid, and the arrangement of which is such that the periphery of said stencil wheel passes through the liquid contained in said tank; and means for rotating said stencil wheel and said carrier at definite speeds relative to one another.

In testimony whereof I affix my signature.
HECTOR RABEZZANA.
